UNITED STATES PATENT OFFICE

CHARLES LA CAVERA, OF CHICAGO, ILLINOIS, ASSIGNOR OF ONE-HALF TO
GEORGE COLOVOS

HAT IRONER

Application filed June 16, 1930. Serial No. 461,381.

This invention relates to a hat ironer and particularly to one that is inexpensive to manufacture and sell and especially useful in small hat cleaning shops where the cost of the hat cleaning and ironing apparatus is of vital importance.

There are many hat cleaning shops in existence at the present time of such nature as to make the cost of a hat ironing machine prohibitive and, consequently, what ironing is done is done by hand with the result that the felt of the hat is not properly compressed as it is when the hat is manufactured.

The present invention contemplates a hat ironing machine which is small and compact, highly efficient in use and which may be manufactured and sold at a moderate price.

An object of the present invention is to provide a hat ironer which is efficient in use and which can be manufactured for sale at a moderate price and wherein the travel of the iron is adjustable, and oscillating cranks are employed to operate the iron and to allow adjustment of the same in use.

Another object of the invention is to provide a hat ironer wherein the movement of the iron is caused by oscillating cranks and in which the period of oscillation may be varied as desired.

Another object of the invention is to provide a hat ironer wherein the iron is moved through a curved path in a vertical plane by a crank having a plurality of parallel members whereby the throw of the crank with respect to the driving mechanism may be varied within certain limits, and whereby the throw of the arm may be varied in a different manner for governing the path of travel of the iron.

A further object of the invention is to provide a hat ironer having a support for a hat form which is adjustable axially so as to subject as much or as little of the hat to the ironing process as is desired.

The above, other and further objects of the invention will be apparent from the following description, accompanying drawings and appended claims.

An embodiment of the invention is illus-

trated in the accompanying drawings and the views thereof are as follows:

Figure 1 is a side elevational view of a machine embodying the present invention showing a portion of the hat form broken away and the cover in section.

Figure 2 is an end view of the machine illustrated in Figure 1 looking at the left-hand end thereof with the cover removed.

Figure 3 is a sectional view taken substantially in the plane of line III—III of Figure 1 with certain parts broken.

Figure 4 is a fragmental portion of a crank showing a latch for retaining the iron out of the way.

The drawings will now be explained.

The form of apparatus chosen to exemplify the present invention is illustrated as comprising a base 1 which is supported by feet 2 and which may be placed in any convenient place for use.

A cover 3 encases the mechanism and rests in a rabbitt 4 formed in the base 1.

A block 5 is supported on the base 1 for receiving a motor 6, which motor is secured to the block 5 by bolts 7 or in any other suitable manner. The block 5 may be integral with the base or may be made separately if desired and in which case it would be attached in any approved manner.

A table 8 is arranged on the base 1 and is block-like in form.

A standard 9 is secured to the base 1 for supporting the hat form A of the machine. A vertical shaft 10 is suitably supported in the standard 9 and maintained therein by collars 11 and 12. A worm gear 13 is keyed to the shaft 10 above the collar 11.

A shaft 26 is supported in bearing blocks 14 and 15 on the table 8 and at one end is provided with a worm 16 in mesh with the worm gear 13 on the shaft 10 and is connected to or forms an integral part of the motor shaft. The shaft 26 is provided with a worm 17 near the motor for meshing with a wheel 18 carried in a stub-shaft supported in a bearing block 19 and suitably supported in the machine. An oscillating arm 20 is pivoted at 21 to the table 8 and is arranged for oscillation in a vertical plane about the

5 pivot 21. The arm is provided with two cranks 22 and 23 which are formed as integral parts of arm 20 and which cranks are parallel and in spaced relation. The crank 22 is slotted at 24 which slot extends from near the upper end thereof to a point below the shaft 19a supported in the bearing block 19. The crank 23 is slotted at 25 from near its upper end to a point near its lower end, that is, a point near where it is connected to the arm 20, which in the present instance is below the shaft 26.

10 A block 27 is slidable within the slot 24 of the crank 22 and a similar block 28 is slid- 70 able in the slot 25 of the crank 23.

15 A block 30 is secured to the gear 18 near its periphery. The block 30 is operatively connected to the block 28 by a pin 31, which block 28 is freely slidable in the slot 25 of the 80 crank arm 23.

20 A bearing block 32 is supported in the machine in axial alignment with the block 19 and supports U-shaped rocker B having two parallel arms 33 and 34. The arm 34 is slotted substantially throughout its length 85 and a block 35 is movable within the slot and may be fixed or clamped anywhere along the slot. The block 35 is connected to the block 27 of the crank 22 by a pin 36.

25 A hat form base 37 which elliptical in plan view is supported by means of a collar 38 on the shaft 10 and is adjustable along the shaft being secured in adjusted position thereon by a set-screw 39. The base 37 has a pin 40 fixed therein and extending upwardly, and another pin 41 spaced from the pin 40 and pivoted at 42 to have springy movement in the base. The base 37 is provided with a depending lug 43 through which passes a 90 screw 44 which is connected to the swinging pin 41 and which is actuated by a wing 45.

30 The hat form A is provided with a central hub 46 which is bored at 47 to receive the end of the shaft 10. The form is made as a shell 95 so that the pins 40 and 41 may engage the inner surfaces of the shell to fasten the form to the form base 37. The form A may, of course, be of any size, shape and contour as desired in order to receive and accommodate 100 hats of various sizes and shapes.

35 Provision of the adjustable form base 37 enables the vertical adjustment of the form so that the iron may engage as much or as little of the surface of the hat as is desired.

40 An arm 48 is pivoted at 49 to the upper end of the arm 33 of the crank member B. A spring 50 engages over the end of the arm 48 adjacent the pin 49 and the adjacent end of the arm 33 to normally urge the iron 51 105 against the hat form A.

45 The iron 51 is pivoted at 52 to the arm 48. The iron 51 is made as a hollow member with a heating element therein which is connected by means of conductors 53 to a source of electrical energy for heating the iron.

5 A counterweight 54 is secured to the member B, and depends below the arm 33 thereof and balances the weight of the iron 51 on the arm 48 as the parts are moved in use.

55 The adjustment of the blocks 27, 28 and 35 in cranks 22, 23 and 34 enables the selection and arrangement of any length of travel of the iron 51 as occasion may demand.

60 The operation of the apparatus is as follows:

65 The dotted position of the iron 51 in Figure 2 shows the lowest point to which the same can be moved. Downward movement of the iron 51 may be adjusted to end at any point above that shown in Figure 2 between 80 said low limit and the apex of the hat form A by suitable positioning of the blocks 27 and 35 in the slots. The spring 50 maintains the iron 51 at all times against the hat form A.

70 A hat to be ironed is placed on the form A which is chosen of proper size, depth and shape to conform to the particular hat being treated and the form then placed on the form base 37 attached thereon by the wing 45. The form A is then adjusted vertically on the 90 shaft 10 by manipulation of the set screw 39 and movement of the form in the proper direction.

75 Should it be desired to wash the hat prior to ironing then the arm 48 may be moved into the dotted line position of Figure 1 where it engages underneath a latch 55 on the upper end of the arm 34 of the member B out of the way. The operator may then wash, clean or otherwise treat the hat on the form A, rotating it if he so desires by operation of the 100 motor 6. The ironing is accomplished by moving the iron 51 against the hat, properly adjusting the blocks 27 and 35 to give the desired angular throw of the iron and then the motor started. This results in rotation of the form A by the shaft 10 through the worm 16 and the worm gear 13—at the same time the gear 18 is driven by the worm 17, 105 rotation of which oscillates the crank 23 and the arm 20, as well as the crank 22. This oscillation is transmitted to the member B through the blocks 27 and 35 thus causing the iron 51 to travel in a curved path from front to back as viewed in Figure 1 and left to right and vice versa as viewed in Figure 2. The extent of movement being controlled, of course, by the adjustment of the blocks 27 and 35 and the gear 18 and member B respectively.

110 The hat form, of course, is being rotated so that the hat thereon is subjected to a uniform ironing pressure and heat as long as the apparatus is operated. The pressure of the iron against the hat is controlled by the 115 spring 50, and might of course, be controlled in some other manner if desired.

120 The cover 3 is applied and as will be observed encloses the motor, the table 8, the standard 9 and the gears and is provided with 125

an aperture 56 for the gear 18 and the cranks 22 and 23.

The apparatus of this invention is one which may be manufactured to be sold at a relatively moderate price so as to be readily available for small hat shops where capital outlay for machinery is limited and where the business does not warrant the purchase of expensive machines.

- 10 It sometimes happens that a hat is ironed without removing the band therefrom, in which event the present machine could be adjusted by lowering the hat form base 37 and the form A so as to subject to the iron 51 only as much of the surface of the hat as appears above the band with the upper edge of the band as the lower limit of travel of the iron 51 in its oscillatory path.

Rotation is imparted to the gear 18 by a worm gear (not shown) supported on shaft 57 which carries a worm gear 58 in mesh with the worm wheel 17 on the shaft 26.

The adjustment of the hat form A on the shaft 10 is such as to accommodate the form to hats of various shapes and sizes so that the machine is readily available for ironing any type, shape or kind of hat which usually is ironed.

33 The invention has been described herein more or less precisely as to details yet it is to be understood that the invention is not to be limited thereby as changes may be made in arrangement and proportion of parts and equivalents may be substituted without departing from the spirit and scope of the invention.

The invention is claimed as follows:

1. A hat ironer, in combination, a rotatably mounted hat form, an iron engageable against said form and movable about the surface thereof in a curved path, a crank pivoted at one end to an immovable pivot for moving the iron in the manner stated, a motor, a gear driven by said motor, a crank pivoted at one end and operatively connected to said gear, connecting blocks engaging said gear and said last mentioned crank for oscillating the crank as said gear is rotated, and connections between said last mentioned crank and said first mentioned crank for varying the degree of throw therebetween whereby the travel of the iron may be varied.

2. A hat ironer, in combination, a vertical shaft, a hat form base adjustably supported on said shaft, a shell-like hat form removably secured to said form base, and clamping means carried by said base for engaging said shell for securing said shell to said base in operative position, said clamping members including a fixed abutment engaging a portion of said shell and a movable abutment for engaging another portion of said shell, and means for moving said movable abutment in a direction to set up wedging action between said abutments and said form.

3. A hat ironing machine including a source of power, a gear driven from said source of power, an oscillating crank, connections between said gear and said crank, another crank movable with said first crank, a third crank operatively connected to said second crank, a hat iron carried by said third crank, said second and third cranks being connected for varying the throw of the third crank by the second crank whereby the variation in throw of the third with respect to the rotation of the gear may be varied over a wide range, said gear and all of said cranks moving in parallel planes.

4. A hat ironer, in combination, a base, a motor standard thereon, a hat form standard thereon, a vertical shaft supported in said hat form standard, a worm gear on said shaft, a shaft connected to said motor supported from said base and carrying a worm in mesh with said worm gear, an iron oscillatable about said form in the plane of said shaft, a U-shaped oscillating bracket having legs oscillatable about a horizontal axis, an arm pivoted to one leg of said bracket and to said iron and swingable about said pivot, an oscillating arm, connections between the motor and said oscillating arm for oscillating the same, and connections between said oscillating arm and said oscillating bracket for imparting oscillation to the iron, said last named connections being adjustable to vary the throw of the iron.

5. A hat ironer, in combination, a base, a motor standard thereon, a hat form standard thereon, a vertical shaft supported in said hat form standard, a worm gear on said shaft, a shaft connected to said motor supported from said base and carrying a worm in mesh with said worm gear, an iron oscillatable about said form in the plane of said shaft, a U-shaped oscillating bracket having upstanding legs and oscillatable about a horizontal axis, an arm pivoted to one leg of said bracket and to said iron and swingable about said pivot, an oscillating arm movable in a plane parallel to the bracket legs, connections between the motor and said oscillating arm for oscillating the same, connections between said oscillating arm and said oscillating bracket for imparting oscillation to the iron, said last named connections being adjustable to vary the throw of the iron, means carried by the bracket for urging said iron against said hat form, and means carried by the bracket for maintaining said iron away from said form when desired.

6. A hat ironing machine, including in combination, a hat form rotatable about a vertical axis, a U-shaped member supported to swing with its arms in vertical planes, an iron supported by one arm of said member and swingable in a curved path from side to side of said form, an oscillating link fixed at one end to swing in a vertical plane parallel

to the arms of said member, connections between said links and the other arm of said member for swinging said member to and fro, and a rotating member connected to said links to oscillate the same.

7. A hat ironing machine, including in combination, a hat form rotatable about a vertical axis, a U-shaped member supported to swing with its arms in vertical planes, an iron supported by one arm of said member and swingable in a curved path from side to side of said form, an oscillating link fixed at one end to swing in a vertical plane parallel to the arms of said member, connections between said links and the other arm of said member for swinging said member to and fro, and a rotating member rotating in a plane parallel to the plane of oscillation of said links and connected to said links for oscillating the same, said connections being adjustable to vary the amplitude of oscillation of said links.

In testimony whereof I have hereunto subscribed my name at Chicago, Cook County, Illinois.

CHARLES LA CAVERA.
